UNITED STATES PATENT OFFICE.

ROBERT M. JOHNSON, OF WESTMORELAND, CALIFORNIA.

IGNITION-SPARK TESTER.

Application filed May 31, 1927. Serial No. 195,297.

This invention relates to a combined ignition spark tester and burglar switch and it consists in the novel features hereinafter described and claimed.

5 The device is termed a spark tester for the reason that the sparks which may be produced across gaps in the circuits of an ignition system may be observed and the conditions of the said circuits or currents ascertained. The device is termed a burglar switch for the reason that means are provided for interrupting the circuits at the gaps between the points thus cutting off the currents to the ignition plugs.

15 An object of the invention is to provide an improved spark indicator and spark plug tester for internal combustion engines, and it includes auxiliary spark gaps adapted to be respectively included in circuit with the 20 spark plugs and whereby the said auxiliary spark gap will be easily visible so that the currents of a spark at any one of said gaps may be readily observed and the proper flow of current to the plugs may be determined.

A further object of the invention is to provide a structure wherein corresponding terminals of the auxiliary spark gaps may be readily adjusted with respect to the 30 acting terminals of said gaps for either closing the circuits at the gaps or varying the length of said gaps to accordingly test the efficiency of the respective spark plugs.

A still further object of the invention is to provide insulating means adapted to be disposed in the gaps and interposed between the terminals to positively prevent sparks from bridging the gaps when it is desired that the flow of the current to the ignition 40 plug should be interrupted, thus providing means for assuring a saving of wear or exhaustion of batteries or other current generator.

In the accompanying drawings:

5 Figure 1 is a face view of the spark indicator.

Figure 2 is a sectional view thereof, cut on the line 2—2 of Figure 1.

Figure 3 is a sectional view thereof, cut 50 on the line 3—3 of Figure 2.

Figure 4 is a transverse sectional view, cut on the line 4—4 of Figure 1.

Figure 5 is a transverse sectional view, cut 55 on the line 5—5 of Figure 1.

Figure 6 is a fragmentary detailed sectional view cut on the line 6—6 of Figure 3.

Figure 7 is a fragmentary plan view of the detail illustrated in Figure 6.

The spark indicator and plug tester comprises a casing 1 provided at one side with 60 a cover 2 having a transparent panel 3. The said casing may be applied to the instrument board of an automobile in any suitable manner. Terminals 4 pass through one side of the casing and are spaced from each other 65 and are connected with circuit wires 5 in a usual manner. Bolts 6 are carried at the same side of the casing and coil springs 7 are mounted upon said bolts. A block 8 is slidably mounted upon the bolts and rests 70 upon the ends of the springs 7 as best shown in Figure 3 of the drawing. Terminals 9 are carried by the block 8 and are spaced from each other and disposed opposite the terminals 4. Nuts 10 are screwed upon the 75 upper end of the bolts 6 and serve to move the block 8 and the points 9 carried thereby toward the points or terminals 4. The points or terminals 9 are connected with current wires 11. The wires 5 and 11 are connected in the ignition circuit (not shown) in any suitable or usual manner. The terminals 4 and 9 are normally spaced from each other at their inner ends to provide gaps as best indicated in Figure 3 of the drawings. 85

A tongue 12 of insulating material is pivotally mounted between lugs 13 provided at the interior of the casing. A shaft 14 is journalled in the lugs and may slide therein and the said shaft is provided with a non-circular or squared section 15 which is slidably received in the tongue 12. Therefore, the tongue 12 may slide along the shaft 14, but the tongue 12 is constrained to turn with the shaft. A sleeve 16 receives the outer portion of the shaft 14 and is provided with a curved slot 17 which receives a pin 18 carried by the shaft 14. The shaft is provided at its outer end with a knob 20.

By adjusting the nuts 10 upon the bolts 100 6, the block 8 may be moved toward or away from the side of the casing 1 which carries the terminals 4. Consequently, the gaps between the terminals 4 and 9 may be regulated with regard to their transverse 105 breadth. By turning the shaft 14, the tongue 12 may be swung from the position shown in Figure 2 of the drawings to a position indicated by the dotted lines in said figure, whereby the said tongue is interposed between the opposite ends of the terminals 4 and 9. Thus the circuits may be

interrupted and the supply of the current to the ignition plugs may be cut off. As the shaft 14 is turned, the pin 18 moves along the curved slot 17 from one end to the opposite end thereof, and consequently, the shafts 14 remains placed at that position to which it is put. As the shaft 14 turns and the pin 18 moves along the slot 17, the shaft 14 slides longitudinally and the non-
circular section 15 thereof slides through the tongue 12.

Thus, it will be seen that means are provided for observing the sparks and for cutting off the supply of current to the spark plugs, and the tongue may serve as a burglar switch for cutting off the current at the spark gaps, thus preventing the battery from running down should the primary switch of the current (not shown) be left on.

While I have particularly described the elements best adapted to perform the functions set forth, it is obvious that various changes in form, proportion and in the minor details of construction may be resorted to, within the scope of the appended claims, without departing from the spirit or sacrificing any of the principles of the invention.

Having described the invention, what is claimed, is:

1. A device of the character described comprising a casing, a block mounted for movement and adapted to form a side of

the casing, aligned terminals carried by the block and an opposite wall of the casing, and a tongue pivoted in the casing and adapted to be moved to a position between the terminals.

2. A device of the character described comprising a casing, bolts mounted at one side of the casing, springs coiled about the bolts, a block slidably mounted upon the bolts and bearing against the springs, means mounted upon the bolts for holding the block at an adjusted position, aligned terminals carried by the block and an opposite side of the casing and a tongue adapted to be interposed between the terminals.

3. A device of the character described comprising a casing, a block movably mounted therein, aligned terminals carried by the block and an opposite side of the casing and a tongue adapted to be interposed between the terminals.

4. A device of the character described comprising a casing, aligned terminals carried by the casing, a shaft journaled in the casing and adapted to slide therein, means for holding the shaft at an adjusted position, a tongue slidably mounted upon the shaft and adapted to turn with the same and adapted to be interposed between the aligned terminals.

In testimony whereof I affix my signatures.

ROBERT M. JOHNSON.
